CLOSURE DEVICE FOR RENDERING
BOTTLES NONREFILLABLE

Jose Soto del Llano, Habana, Cuba, assignor of
one-fourth to Ricardo Moré Ferrer, Habana,
Cuba

Original application March 21, 1942, Serial No.
435,710, now Patent No. 2,318,382, dated May
4, 1943. Divided and this application March
15, 1943, Serial No. 479,194. In Cuba June 21,
1941

2 Claims. (Cl. 215—23)

1

This invention relates to non-refillable containers, particularly to the bottles adapted to contain high quality beverages, such as, for instance, spirituous liquors, and it has for its object the provision of a closure enclosing a slideable valve which in the normal position of the bottle will tend to seal the latter by gravity and which carries secured thereto by a pivotally connected flexible fastening member a free dropping weight which whenever the container is inclined in any inverted position or placed horizontally and any liquid is intended to be injected from the outside into the exhausted container, such weight will act by gravity causing the valve to slide and seal the inlets for the air and the liquid to be introduced in the container for refilling purposes.

This application is a division of United States application Serial No. 435,710 now Patent No. 2,318,382, dated May 4, 1943.

The invention is described with reference to the figures of the accompanying drawing; of which:

Fig. 1 is an outer elevational view of a bottle provided with the closure being the subject-matter of this invention, the metal strap for retaining the closure being shown partly cut away.

Fig. 2 is a diametral vertical sectional view of the closure and the upper end of the bottle in the normal position of same.

Fig. 3 is a view similar to that of Fig. 2, showing the closure parts in an inclined or inverted position of the bottle.

Fig. 4 is a detailed view showing in outer elevation the closure valve-carrying member, in the normal position of the bottle.

Figs. 5 and 6 are cross-sectional views on lines 5—5 and 6—6 of Fig. 4.

Fig. 7 is a detailed view showing the closure valve-carrying member in a diametral vertical section, in the fully inverted position of the bottle.

Fig. 8 is a detailed view showing in diametral vertical section the closure valve-carrying member, in the horizontal position of the bottle.

Fig. 9 is a perspective view of the valve and its weight.

Fig. 10 is an elevational view of a slideable auxiliary cap adapted to cover the outer end portion of the valve-carrying member.

This closure is composed of a casing 1, either cylindrical or of square section, which is opened at its lower end and extended above in a portion of reduced diameter 2, and the same is preferably made of an interiorly tinned metal or of an alcohol-proof plastic material, said

5 casing being placed on an annular packing 3 disposed on the upper edge of the bottle 4 and being retained in position by a metal strap 5 fitted on a shoulder 6 formed on the neck of bottle 4 and on the conical or pyramidal portion 7 joining the casing 1 and its reduced portion 2.

10 The reduced portion 2 has its upper end closed and provided with a pass opening 8, and the conical or pyramidal portion 7 has an inner annular flange 9 whose aperture has threads 10 to engage the threaded section 11 of a valve-carrying cylindrical member 12 whose lower half portion is of a thicker wall to provide an upper valve seat 13 and is provided with a horizontal flange 14 extending outwards to form a stop against the inner flange 9 of the casing beneath same, whereby the member 12 can be threadedly inserted within the casing 1 while the latter has not yet been placed on the bottle 4.

15 The lower half portion of said valve-carrying cylindrical member 12 has a lower opening 15 and a series of side openings 16 in circular arrangement at its peripheral wall. The upper half portion of said valve-carrying cylindrical member 12 is of a wall thinner than the wall of the lower half portion and is opened above, the same being adapted to receive the slideable valve 17 which fits into same and when resting on the seat 13 covers a series of small openings 18 20 formed in circular arrangement in said upper half portion member 12 near the seat 13, the upper half portion of the valve-carrying member 12 being spaced from the reduced portion 2 of the casing 1 to provide an annular space 19, and the lower half portion of said valve-carrying member 12 is also spaced from the casing 1 to provide an annular space 20.

25 As the bottle 4 is placed in an inverted or inclined position to empty it, the closure parts are placed in the position indicated in Fig. 3 of the drawing, that is, the cap 24 slides down until its raised edge 25 strikes against the closed end of section 2 of the casing, thereby uncovering the series of small openings 18, and the valve 17 also slides down until it strikes against the closed outer end of cap 24 and carries along with it by means of the link 22 the weight 23 until resting on the edge of opening 15, whereby outer air has free access through outer opening 8, notches 26 of cap 24, annular space 19, openings 18, inner hollow of cylindrical member, openings 16 and annular space 20, while the inner liquid in bottle 4 finds its way out through the side openings 16 from the annular space 20, entering into the valve-carrying cylindrical member 12, leaving

ing the latter through the small openings 18, and finally circulating through annular space 19 and notches 26 toward the outlet 8.

Assuming the bottle in its inverted or inclined position, if an attempt should be made to inject liquid by pressure through opening 8, the liquid will enter and push inwardly the cap 24 and the valve 17, whereupon it will shut off the communication between annular space 19 and the inside of the valve-carrying cylindrical member 12 through small openings 18. If the bottle 4 is placed in horizontal position, or if in this position the bottle is submerged in a filled tank for re-filling purposes, to facilitate the egress of inner air, the weight 23 being adapted to drop freely, in virtue of its own weight and the conical shape of both of its ends, it will slide on the edge of opening 15, drop into the inner space of casing 1 (Fig. 8) and pull valve 17 which, therefore, will slide inwards and obturate the series of small openings 18, thereby interrupting the egress of inner air and the entry of outer liquid. The valve 17 has interiorly threaded a screw 21 to which is pivotally connected a link 22 from which is dependent by pivotal connection a loose weight 23 which remains depending across and beneath the opening 15. Said weight 23 is of double frustoconical shape with its larger section at the centre and having there a diameter greater than that of opening 15 and its ends sharpened so that in the inclined or inverted position of the bottle (Fig. 3) it will remain seated on the edge of opening 15, thereby sealing the latter.

Preferably, the upper half portion of the valve-carrying member 12 will carry adjustable and slidable mounted thereon a cap 24 opened below and closed above, which has a raised upper edge 25 provided with a series of notches 26 forming a sort of crown.

The functional operation of this closure is as follows: In the upright or normal position of the bottle 4 (Fig. 2) no access is had into the bottle 4, due to that the valve 17 rests by its own weight on the seat 13 with the aid of the depending weight 23 connected thereto, and the cap 24 also rests by its own weight on the intermediate projecting portion of the member 12 covering thereby all the small openings 18 in the upper half portion of the member 12, thereby rendering impossible the refilling of the bottle 4 in its upright position.

It is obvious that the shape of the closure device as well as the nature of the material of which same is made may be varied, without by this reason the essential character of the invention being considered as altered, within the scope of the claims hereinafter.

What I claim is:

1. In a closure device for rendering bottles non-refillable, when attached to the mouth of the same, the combination of an outer casing with openings at its top and bottom and adapted to

rest with its bottom against the mouth of the bottle, a cylindrical valve carrying member within said casing and having its intermediate portion fixedly connected with an intermediate portion of the casing, said valve carrying member having tubular end portions projecting from its intermediate portion in opposite directions and providing annular spaces between said end portions and the casing, said cylindrical valve carrying member having a valve seat between its ends and the walls of the tubular end portions of said valve carrying member being provided with openings at each side of said valve seat, a valve slideable by gravity within one projecting tubular end portion of the valve carrying member, a weight extending from the other tubular end portion of the valve carrying member and being flexibly connected with said valve, and a cap slideable on the projecting tubular end portion containing said valve and adapted to free and obstruct respectively the openings in said last named projecting tubular end portion of the valve carrying member, and means for inviolably securing said outer casing to the neck of the bottle.

2. In a closure device for rendering bottles non-refillable, when attached to the mouth of the same, the combination of an outer casing with openings at its top and bottom and adapted to rest with its bottom against the mouth of the bottle, a cylindrical valve carrying member fixed within said outer casing, and a valve movable in said valve carrying member, said outer casing having a stop flange at the end opposite its mounting end on the mouth of the bottle and being provided with an inwardly extending flange between its top and bottom, the valve carrying member being fixed between its ends to said inwardly extending flange of said outer casing and having tubular projections extending from the point of attachment to said flange in opposite directions into the casing, each of said projecting portions of the valve carrying member being provided with a plurality of peripherally spaced openings, said valve carrying member having a valve seat intermediate said pluralities of peripherally spaced openings, said valve being slideable in one tubular projection of the valve carrying member, a weight being flexibly connected with the valve and projecting from the opposite tubular projection of the valve carrying member, and a hood slideable over that tubular projection of the valve carrying member containing said valve, said hood being movable between the inwardly extending flange and the stop flange of said outer casing and being adapted in one end position to obstruct the peripherally spaced openings in that tubular projection containing said valve and being limited in its movement in the opposite direction by said stop flange of the outer casing, and means for inviolably securing the outer casing to the neck of the bottle.

JOSE SOTO DEL LLANO.
